COMBINED ASH TRAY AND SMOKING TUBE OR SIMILAR ARTICLE

Adam Kurant, Youngstown, Ohio

Application April 27, 1954, Serial No. 30,215

Term of patent 14 years

(Cl. D85—2)

To all whom it may concern:

Be it known that I, Adam Kurant, a citizen of the United States, residing at Youngstown, in the county of Mahoning and State of Ohio, have invented a new, original, and ornamental Design for a Combined Ash Tray and Smoking Tube or Similar Article, of which the following is a specification, reference being had to the accompanying drawing, forming a part thereof.

The figure is a perspective view of a combined ash tray and smoking tube or similar article, showing my new design.

The opposite side, not shown, has substantially the same appearance as the side shown in the figure.

I claim:

The ornamental design for a combined ash tray and smoking tube or similar article, as shown and described.
